(57) **CLAIM**

We claim the ornamental design for a bottle, as shown.

DESCRIPTION

FIG. 1 is a perspective view of our bottle design.

FIG. 2 is a front elevation view of our bottle design.

FIG. 3 is a rear elevation view of our bottle design.

FIG. 4 is a left side view of our bottle design.

FIG. 5 is a right side view of our bottle design.

FIG. 6 is a top plan view of our bottle design; and,

FIG. 7 is a bottom plan view of our bottle design.

Those areas of the figures represented by broken lines are visible environmental structure and are not part of the claimed design.
